(57) **CLAIM**

The ornamental design for a V-buckle as shown and described.

DESCRIPTION

FIG. 1 is a top plan view of a first embodiment of a V-buckle, showing my new design;

FIG. 2 is a left side view thereof;

FIG. 3 is a right side view thereof;

FIG. 4 is a top perspective view thereof;

FIG. 5 is a rear view thereof;

FIG. 6 is a front view thereof;

FIG. 7 is a bottom plan view thereof;

FIG. 8 is a top plan view of a second embodiment of a V-buckle, showing my new design;

FIG. 9 is a left side view thereof;

FIG. 10 is a right side view thereof;

FIG. 11 is a top perspective view thereof;

FIG. 12 is a rear view thereof;

FIG. 13 is a front view thereof; and,

FIG. 14 is a bottom plan view thereof.

The broken lines in the drawings represent portions of the V-buckle and form no part of the claimed design.

1 Claim, 14 Drawing Sheets
